UNITED STATES PATENT OFFICE

97,469

DESIGN FOR A JAR

William Bullard Durant, Belmont, Mass.

Application March 20, 1935, Serial No. 55,959

Term of patent 14 years

To all whom it may concern:

Be it known that I, William Bullard Durant, a citizen of the United States, residing at 5 Fieldmont Road, Belmont, in the county of Middlesex and State of Massachusetts, have invented a new, original, and ornamental Design for Jars, of which the following is a specification, reference being had to the accompanying drawing, forming a part thereof.

The figure is a perspective view of a jar showing my new design.

I claim:

The ornamental design for a jar, as shown.

WILLIAM BULLARD DURANT.
